UNITED STATES PATENT OFFICE.

EDGAR W. GENT, OF MORRISTOWN, NEW JERSEY, ASSIGNOR TO WESTERN ELECTRIC COMPANY, INCORPORATED, OF NEW YORK, N. Y., A CORPORATION OF NEW YORK.

TELEPHONE SWITCH.

Application filed October 24, 1922. Serial No. 596,546.

To all whom it may concern:

Be it known that I, EDGAR W. GENT, a citizen of the United States, residing at Morristown, in the county of Morris, State 5 of New Jersey, have invented certain new and useful Improvements in Telephone Switches, of which the following is a full, clear, concise, and exact description.

This invention relates to automatic telephone exchange switching apparatus and particularly to the so-called coordinate switches of the type employed in automatic telephone exchanges.

This invention is particularly adaptable 15 to a switching system of the type generally disclosed in British patent to Western Electric Company, Limited, No. 183,438, accepted September 6, 1923. It will be apparent to those skilled in the art that this invention may be applied equally well to perform 20 other switching functions.

Heretofore, and particularly in the switch disclosed in the above mentioned British patent, the practice has been to have a rotatable bar assigned to each group of incoming lines. Other rotatable bars are assigned 25 individually to link conductors and still others to outgoing lines or trunks. At the intersections of the bars are provided camming cards for operating sets of movable 30 contacts and bringing them into engagement with sets of stationary contacts. Each of said bars is common to a plurality of the camming cards, so that if a bar becomes inoperative it throws out of operation a plurality of contact sets.

The object of this invention is to provide a simple and economical switching structure 35 of the character above described having operating means individually associated with each set of active contacts.

This object is accomplished by providing a pair of electromagnets for each contact set. The successive energization of the magnets of any pair is effective in moving a camming card in such a manner as to effect an engagement between sets of active and 45 passive contacts.

In accordance with another feature of 50 this invention the passive contacts are obliquely disposed and embedded between two insulating members, so that upon actuation of a camming member, a wiping en-

gagement is effected between its associated set of active contacts and a corresponding 55 set of passive contacts.

The invention will be more readily understood from the following description, reference being had to the accompanying drawings in which Fig. 1 is a partial assembly 60 view of a switch embodying the features of this invention. Fig. 2 is a sectional view taken along the line AB of Fig. 1 and viewed in the direction indicated by the arrows. Fig. 3 is a sectional and partial assembly view of the grid showing the clamps for securing the wires between the insulating plates. Fig. 4 is a circuit which may be employed for controlling the operation 65 of the magnets employed in this switch. 70

The grid structure employed in mounting the sets of passive contacts such as 5, 6, 7 and 8 and 9, 10, 11 and 12 consists of two apertured insulating plates 1 and 2 between which a soft fibrous material 90 such as tar paper is inserted for the purpose of embedding the passive contacts therein, when the insulating plates 1 and 2 are pressed together and held in close proximity by the eyelets 4'. 75

The structure may be of any desired width and height to accommodate as many vertical rows of active contact sets and as many sets per row as may be required depending upon the switch capacity desired. 85 The active contact wires 13, 14, 15 and 16, etc. are made preferably of bare wire and are embedded in vertical bars 21 of insulating material, which are supported at their end portions on the switch frame (not 90 shown).

Each set of active contact wires is provided with an operating card 22, slidably arranged in a guide 23. Each card has a number of apertures 24, 25, 26 and 27 95 through which the active wires 13, 14, 15 and 16 extend in juxtaposition with their associated passive contacts or link conductors 9, 10, 11 and 12, and into the grid apertures 28, 29, 30 and 31, respectively. 100

The operating cards 22 are shown supported on movable supports 32, which, like the active contact wires have one end thereof embedded in the vertical bar 21. The free ends of the movable supports 32 pass 105 through apertures 33 in the guides 23 and

engage their respective camming cards 22. The aperture 33 serves to limit the upward movement of the card 22 thereby preventing distortion of the active contacts should the armature 36 of the operating magnets such as 34 and 39 tend to drive the card 22 beyond its operated position. The supports 32 are springs, tensioned to move the active contacts down and out of engagement with the passive contacts.

Each operating card 22 is provided with a set of operating magnets such as 35 and 40 which function sequentially. The operation of a magnet such as 34 causes the projection 43 on armature 36 to assume an operable position relative to the card 22, whereas a magnet such as 39 upon energizing thereafter, causes the card 22 to be forced upwardly in the guide 23. The armature 36 which is common to both magnets in a set is also provided with two right angularly disposed projections which are located in close proximity with the poles of the magnets in its respective set, and are adapted to be attracted thereby. A coupling 38 is employed to mount the armature 36 on the switch frame 41 and to permit it to have a universal movement relative thereto. The sequential operation of the magnets in any set moves the card 22 associated with said set upwardly, causing the active contacts to be carried upwardly and due to the oblique disposition of the passive contacts relative to the direction of approach of the active contacts, a wiping engagement is effected between said active and passive contacts.

From the foregoing description it is evident that the conjoint operation of the two magnets in a set causes the establishment of a connection between the active and passive contacts of that set, and it is to be noted that by means of the notched portion 43 of armature 36 such a connection is maintained as long as the operating magnet such as 39 remains energized regardless of whether or not the associated selecting magnet 34 becomes deenergized.

Having described the switch structure and its operation the following description made 50 with reference to Fig. 4 will be directed to a circuit employing a switch of the nature heretofore described. There are shown two groups of two incoming lines, the first group containing lines 147 and 148 and the second 55 group containing lines 149 and 150.

Let it be assumed that the subscriber on line 148 wishes to converse with another subscriber whose line is to be reached over the outgoing trunk 179.

60 The subscriber on line 148 upon removing his receiver from the switchhook establishes a circuit for the energization of the line relay 154. This circuit extends from ground, left-hand winding of relay 65 154, back contact and outer left-hand arma-

winding of magnet 152 to battery and ground. Continuing from conductor 114 circuits may be traced through the normal contacts of magnet 139, 139¹ and 139¹¹ 5 through their respective windings to grounded battery. Magnets 152, 139, etc. become energized in this circuit and thereupon cause the lifting of their associated armatures 36 however only the cards 22 individual to magnets 152 and 139¹ are operated whereupon a circuit is established which may be traced from conductors 13, 14, 15 and 16, through the conductors 9, 10, 11 and 12, respectively, to conductors 160, 161, 162 and 163, respectively. A circuit is now established from grounded contact and right-hand armature of relay 146, conductor 162, conductor 11, front contact of the inner armature of magnet 152, winding of magnet 152 to battery and ground and in parallel therewith through (a) magnets 139, 139¹, etc and (b) winding of cut-off relay 155 to battery and ground. Magnet 152 locks up in the circuit just traced and maintains the connection until the conversation has ceased and the called party replaces the receiver on the switchhook. The effect of replacing the receiver on the switchhook of the calling line will be discussed herein- 30 after. Cut-off relay 155 becoming energized opens the circuit for line relay 154 which retracts its armatures and opens the circuit for both the vertical columns of selecting magnets which include magnets 134 and 164, so that these magnets release their armatures and the connection is held through the switch by the continued energization of magnets 152 and 139¹. As soon as line 148 is extended to the trunk 179 as 35 a result of the operation of magnets 152 and 139¹ a circuit through the winding of relay 151 is completed over the loop of the substation and this relay remains energized during the establishment of the connection. 40 Relay 151 maintains relay 146 energized by placing a ground on the winding of relay 146 as a substitute for the ground which is now removed by the retraction of armatures of magnet 164. 45 When the subscriber on line 148 replaces the receiver on the switchhook and opens the loop of this line, relay 151 becomes de-energized and a short time later relay 146 retracts its armature, removing ground from conductor 162 and allowing magnets 152, 139 and 139¹, etc., to become deenergized, whereupon the operated cards are restored to normal and the connection disrupted. 50 It is to be noted that should the subscriber on line 147 initiate a call during the period in which line 148 is being connected to the trunk 179, the magnet 134 being energized during the establishment of the connection opens the battery circuit for all the other 55 selecting magnets. If two lines in the same vertical group such as 148 and 150 call at the same time, the energizing circuit for magnet 152 will be held open at the back contacts of the line relay 159 for line 150 until the line relay 159 becomes deenergized 70 as a result of the connection of line 150 with an outgoing trunk after which the calling line 148 may be extended. The operating magnets 152, 175, etc. associated with the upper group of lines have 75 their lower armatures connected in a start wire circuit in order that the ground coming from the intermediate armature of the trunk selecting magnet such as 157 will be connected to the first idle magnet in the 80 group. A similar start wire circuit is provided for the operating magnets associated with the group of lines 149, 150, etc. A start wire circuit is also provided for the trunks in order to connect an incoming 85 line to the first idle trunk. For instance, if trunk 179 had been busy when line 148 called, the ground from the inner armature and front contact of relay 134 would have been extended through the inner armature 90 and back contact of relay 164, inner left-hand armature and front contact of relay 146 to the selecting magnets associated with the trunk 156. 95 What is claimed is: 1. In a switching mechanism, a set of passive contacts, a set of active contacts, a pair of electromagnets associated with said active contacts, an armature common to said magnets and capable of a universal movement, 100 and means effective upon the conjoint operation of said electromagnets whereby said armature moves said active contacts into engagement with said passive contacts. 2. In a switching mechanism, sets of active contacts, sets of passive contacts, a card for each set of said active contacts, an armature for each of said cards, and a pair of electromagnets for controlling the movement of each of said armatures, to cause inter- 105 engagement between said active and passive contacts. 3. In a switching mechanism, sets of active and passive contacts, a plurality of pairs of electromagnets therefor, an armature for each pair of magnets and mounted on the switch frame through the instrumentality of a universal joint, and a movable member cooperating with said armature upon the conjoint operation of said pairs of magnets 110 to move a set of active contacts into engagement with a set of passive contacts. 115 4. In a coordinate switch structure, sets of normally disengaged active and passive contacts, an operating mechanism for each set of said active contacts comprising an armature capable of movement in two different planes, a magnet for actuating said armature in one of said planes, and another magnet for actuating said armature in the other of 120 125 130

said planes, the conjoint operation of said magnets effecting an engagement between a set of active and passive contacts.

5. In a coordinate switch structure, sets of normally disengaged active and passive contacts arranged in coordinate rows, electromagnetic means for operating said active contacts comprising a plurality of cooperating electromagnets arranged in pairs, and an armature associated with each pair of said magnets, the sequential energization of the magnets in any of said pairs being effective to move said armature in such a manner as to effect an engagement between a set of said active and passive contacts.

6. In a coordinate switch structure, a grid comprising apertured insulating plates, contacts held in position thereby, other contacts disposed at right angles to first said contacts and extending from the apertures in said plates, and means for moving said last contacts into engagement with said first contacts.

7. In a coordinate switch structure, sets of normally disengaged active and passive contacts arranged in coordinate rows, means for selectively operating said active contacts, said means comprising a row of multiplied electromagnets associated with each row of active contacts, and another row of electromagnets associated with each row of passive contacts, the energization of the magnets in the first mentioned row followed by the energization of the magnets in the sec-

ond mentioned row being effective to inter- 35 engage a set of passive and active contacts to establish a circuit connection.

8. In a switching mechanism, electromagnetic means, an armature associated with said electromagnetic means and attractable 40 in a plurality of directions, a contact operating device, means responsive to a particular sequence of movement of said armature to render said contact operating device effective.

9. An electromagnetic device comprising a plurality of windings, and an armature common to said windings and adapted to be attracted in different paths thereby.

10. In a switch, a fixed contact and an 50 elongated movable contact adapted to approach said fixed contact to effect a wiping engagement therewith, said fixed contact being obliquely disposed in a plane extending substantially at right angles to said movable contact.

11. A switch comprising movable contacts arranged in one plane, fixed contacts arranged in another plane and obliquely disposed to said first contacts, and means for 60 moving said first contacts in their plane to effect a wiping engagement between said movable and fixed contacts.

In witness whereof, I hereunto subscribe my name this 21st day of October, A. D. 65 1922.

EDGAR W. GENT.
